United States Patent Office

Des. 214,996
Patented Aug. 19, 1969

214,996

FOOD DISPLAY PACKAGE

Jack V. Cline, Hinsdale, Ill., assignor to Tee-Pak, Inc.

Filed Dec. 20, 1967, Ser. No. 9,871

Term of patent 14 years

Int. Cl. D9—04

U.S. Cl. D9—191

FIG. 2

FIG. 1

FIG. 1 is an isometric view of a food display package, and

FIG. 2 is a side elevation thereof on a reduced scale.

The rear side of the package shown in FIG. 2 is substantially the same as shown in FIG. 2 and the bottom of the food display package is substantially flat and unornamented.

I claim:

The ornamental design for a food display package, substantially as shown and described.
